UNITED STATES PATENT OFFICE.

WILLIAM B. FOSTER, OF UTICA, NEW YORK, ASSIGNOR TO FOSTER BROTHERS MANUFACTURING COMPANY, OF UTICA, NEW YORK, A CORPORATION.

DETACHABLE KNOT OR FASTENER FOR COILED SPRINGS.

Application filed November 20, 1922. Serial No. 601,994.

To all whom it may concern:

Be it known that I, WILLIAM B. FOSTER, a citizen of the United States, and a resident of Utica, in the county of Oneida and State 5 of New York, have invented certain new and useful Improvements in Detachable Knots of Fasteners for Coiled Springs; and I do hereby declare that the following is a full, clear, and exact description thereof, 10 which will enable others skilled in the art to which it appertains to make and use the same, reference being had to the accompanying drawings, and to the reference numerals marked thereon, which form part of this 15 specification.

My present invention relates to a detachable knot or fastener for coiled springs.

The purpose of my invention is to provide a detachable knot or fastener for coiled 20 springs of novel and improved construction and which is noiseless in use.

A further purpose is to provide a detachable fastener which can be readily attached and detached without the use of tools and 25 without having to permanently bend or straighten any of the loops or hooks in the wire forming the coiled spring.

A further purpose is to provide a detachable knot the parts of which can be permanently shaped before the tempering 30 process and readily attached without distortion and after the tempering process has been effected readily attached or detached without distorting the spring or permanently bending the parts forming the knot.

A further purpose is to provide a coiled 35 spring having a detachable knot of such construction that the end of said knotted spring when detached may be threaded directly through an adjacent coiled spring or through a fastening clip or loop and then the knot readily assembled.

A still further purpose is to provide a detachable knot particularly well adapted 40 to have a coil of an adjacent spring connected thereto and still lie flat and noiseless.

Further advantages and purposes of this 45 invention will appear from the specification and claims herein.

Fig. 1 is a plan view of the top portion 50 of two adjacent and interlocked coiled springs having a detachable fastener or knot embodying my invention.

Fig. 2 is a side elevation of a single coiled 55 spring having my knot.

Fig. 3 is a top view of the upper part of said coiled spring with the knot detached and Fig. 4 is a side view of the spring with a knot detached.

Fig. 5 is a cross section on line 5—5 of 60 Fig. 1.

Referring to the drawings in a more particular description, the detachable knot or fastener is shown in connection with the upper end of a coiled spring 7 of the so-called hour-glass type but it will be apparent from the description and drawings herein that the invention may be applied to both ends of the spring and also may be applied to any form of spring where the extremity 8 70 of the last, or, as shown in the drawings, upper coil 9 is spaced slightly out from but on nearly the same horizontal level as the opposite and beginning or inner end 10 of said outer or top coil 9.

75

As the wire forming the complete coil spring extends from the body 7 of the spring towards the last or outer, and as shown in the drawings, top coil 9 there is formed in the wire and in said inner end 80 of said top coil 9 an outwardly extending and horizontally arranged U-shaped loop 12. This loop will be of a depth two or three times the diameter of the wire and after the loop is formed the wire will continue on in about the same curve to form the outer coil 9.

85

At the extremity or outer or free end 8 of the upper coil 9 there is formed a double hook or S-shaped hook 13 as seen in side 90 elevation as in Figs. 2 and 4. The first part 14 of said hook, that is the part nearest the body of the upper coil 9, extends downwardly, the second part 15 extends upwardly to about the horizontal plane of the upper coil 95 9 and then the third and last part 16 extends downwardly.

95

As ordinarily formed to get a level topped spring and also to have the parts of the knot stay snugly and noiselessly in place after 100 once assembled, the spring when formed will have the upper coil 9 sloping upwardly towards its free end and with the S-shaped hook 13 slightly above the U-shaped loop 12 at the other or beginning end of the last 105 coil as plainly indicated in Fig. 4 which is a side elevation of the relevant parts of the coiled spring before the knot is assembled. In assembling the knot the last or outer half of the last coil 9 is temporarily bent 110

down sharply towards the body 7 of the spring and the S-shaped hook passed below the loop 12 and inside the circle of the last coil 9 and then brought out so that the 5 second and third portions 15 and 16 of the S-shaped hook engage the right-hand leg of the U-shaped loop 12 as the parts are seen in the drawings; then by releasing the upper coil said upper coil springs back to 10 normal assembled position as shown in Fig. 2 with the first part 14 of the S-shaped hook to the left of the left-hand leg of the loop 12 and with the middle or second portion 15 of the S-shaped hook passing upwardly between the two legs of the loop 12 and out against the inner surface of the connecting part or bottom of the U-shaped loop. 15 The knot may be readily and manually detached by reversing the process just outlined. It will be seen that the knot may be readily attached and detached without the use of tools and without having to bend or permanently distort any part of the spring or of the parts of the knot. 20 Both parts of the knot, that is the S-shaped hook and the U-shaped loop are simply and relatively open, that is free from complete loops or crossing wires and so may be readily made by simple machinery. 25 These parts may be readily made after the regular convolutions have been made by the usual coiling machine or the coiling machine may be modified to form the S-shaped hook at the end or even the U-shaped loop back therefrom. It will be seen especially that the parts of the knot may be left disconnected during the tempering process and so will not be distorted by the tempering process and slight variations in the form of the spring incident to the tempering process will not affect the assembling or efficiency of the knot. 30 As the spring may be readily assembled or disconnected and as its two parts are relatively small and free from large projections the spring is particularly well adapted to be threaded onto solid coils of other springs or through connecting loops going to other springs and then have this knot assembled and so complete the assembling of a set of springs. It will be seen, moreover, that the knot here described is well adapted to have the wire of a coil of an adjacent spring pass close to the knot as is especially shown in 35 Fig. 1. When the springs are so connected the regular curved wire as the portion 17 of one coiled spring will pass over or through the knot on the other coiled spring by the wire of the part 17 passing underneath the wire of the knotted coil just to the left of the first part 14 of its S-shaped hook and then passing to the right back of said part 14 and over both legs of the U-

shaped loop and back of the upper portions of the second and third parts 15 and 16. 40 The interlocking of the plain curved piece 17 does not distort the horizontal arrangement of the top coil of either spring and holds the two springs from displacement horizontally and also strengthens each 45 spring against vertical pressure as the springs are so interlocked vertically that one cannot be depressed without depressing the other also. 50

What I claim as new and desire to secure 55 by Letters Patent is:

1. A detachable knot or fastener for a coiled spring comprising an S-shaped hook at the free end of the coiled spring arranged at right angles to the plane of the end coil 80 of the spring and an outwardly projecting U-shaped loop in the end coil of the spring opposite to and detachably engaging said S-shaped hook.

2. A detachable knot or fastener for a coiled spring comprising an S-shaped hook at the end of the coiled spring, the first part of said S-shaped hook extending from the plane of the end coil towards the other end of the spring, the second part returning to 90 wards said plane and the third part extending towards the other end of the spring and an outwardly projecting U-shaped loop in the upper coil of the spring opposite to and detachably secured to said S-shaped 95 hook.

3. A detachable knot or fastener for a coiled spring comprising an S-shaped hook at the end of the coiled spring, the first part of said S-shaped hook extending from 100 the plane of the end coil towards the other end of the spring, the second part returning towards said plane and the third part extending towards the other end of the spring and an outwardly projecting U- 105 shaped loop in the upper coil of the spring opposite to and detachably secured to said S-shaped hook through said first part of the S-shaped hook passing down outside one arm of said U-shaped loop and said second 110 part of the S-shaped hook ascending between the arms of said loop and said third part of the hook passing over the other arm of said loop and downward therebeyond.

4. A detachable knot or fastener for a 115 coiled spring comprising an S-shaped hook at the end of the coiled spring arranged at right angles to the plane of the end coil of the spring and an outwardly projecting U-shaped loop in a previous coil of the 120 spring opposite to and detachably engaging said S-shaped hook.

In witness whereof I have affixed my signature, this 30th day of October, 1922.

WILLIAM B. FOSTER.
